UNITED STATES PATENT OFFICE.

EDWARD P. ARSNEAU, OF SPOKANE, WASHINGTON.

CROSSCUT SAW.

Application filed June 19, 1922, Serial No. 569,509. Renewed March 2, 1925.

To all whom it may concern:

Be it known that I, EDWARD P. ARSNEAU, a citizen of the United States, residing at Spokane, in Spokane County, and State of Washington, have invented certain new and useful Improvements in Crosscut Saws, of which the following is a specification.

My present invention relates to improvements in cross cut saws, of the power operated, continuous, or chain-tooth type, and is especially adapted for cutting down or felling standing trees, and cutting up the timber or logs.

The primary object of the invention is the provision of a strong and durable device of this character which is simple both in construction and operation, is composed of a practical minimum of parts and of comparatively light weight, and which may be manipulated with facility by the sawyers.

With these ends in view the invention consists in certain novel combinations and arrangements of parts between the supporting and operating parts, and novel features of construction as will be hereinafter more specifically pointed out and claimed.

In the accompanying drawings I have illustrated one complete example of the physical embodiment of my invention wherein the parts are combined and arranged according to the best mode I have thus far devised for the practical application of the principles of my invention.

Figure 1 is a plan view of a power operated saw of this type constructed according to and embodying my invention.

Figure 2 is an enlarged detail view at one corner of the yoke shaped casing or housing of the implement showing the power sprocket wheel and chain saw.

Figure 3 is a view of the same portion of the housing at the rear of the view of Figure 2 showing means for holding the implement in working position to the log or work to be cut.

Figure 4 is an enlarged, detail sectional view at line 4—4 of Figure 1 illustrating the guiding means for the chain saw as it passes around the yoke or arched housing.

The casing or housing for the chain saw, as shown in Figure 1 is in the form of a yoke, or arched frame, and comprises complementary, spaced, face plates 1, 1 of metal, cut to the required U-shape, and with widened ends. Between the legs of the

yoke an inner wall and outer wall are provided, the latter designated as 2, and the former made up of three complementary strips 3 extending around inner boundary of the yoke and fixed between the face plates of the housing. Between the adjoining three strips are interposed two, spaced guide plates 4, 4, forming a track or guide way around the arch or curved portion of the yoke-shaped housing, and within the housing. The two legs of the yoke are joined by a bridge member 5, and these described members are riveted or bolted together in suitable manner to form a rigid and well braced structure for enclosing and guiding the chain saw designated as a whole by the numeral 6 and made up of links with link pins at 6'.

The links of the chain are arranged in pairs with cutting-teeth links 7 and 7' and intermediate scraping-teeth links 8.

The pairs of cutting-teeth links and the intermediate clearing-teeth links 8 are hinged together as usual on the pins 6' and 80 as the chain saw is operated they cut and clear a kerf in the work, advancing as the sawing operation progresses in usual manner.

At the back of the chain, which is formed as a sprocket chain, the links, or some of them, are fashioned with sprocket teeth 9 for co-action with the power sprocket wheel 10. Around its periphery the sprocket wheel is provided with rollers 11, spaced apart, and performing the function of the usual teeth on a sprocket wheel. The chain saw passes around the sprocket wheel, which as shown is located at the end of one leg of the yoke near the termination of 95 the bridge 5, and the rollers exert their power from the wheel on the sprocket teeth 9 of the chain, the teeth and rollers being spaced in predetermined relation.

Circular side plates or rings 12 are attached at each side of the sprocket wheel to enclose the rollers, and also to form guides for the chain saw in turning around the wheel. The wheel is fixed on its shaft 13 which is journaled in the yoke in suitable manner, and extends through the two plates 1, 1, of the yoke.

In the end of the leg of the yoke opposite to the power wheel 10 a guiding sprocket wheel 14 is journaled, and it will be apparent that the endless chain or continuous flexible saw is driven from the power

sprocket wheel, passes around the arch or curved end of the yoke, around the guide sprocket and across the bridge 5 where it is guided and held in operative position. 5 The bearings 15 for the guide sprocket may be adjusted in usual manner to take up slack in the chain saw, and to compensate for wear of parts.

The chain saw is driven from a suitable 10 source of power through the medium of a flexible shaft 16' shown in Figure 1, which is coupled with the power shaft 17 that forms a continuation thereof and is journaled in bearings 18 on the exterior of the 15 saw housing or yoke adjacent to the sprocket shaft 13, for transmission of power thereto.

A customary type of clutch 19 is illustrated 20 on the power shaft for throwing the saw into or out of operation, and the clutch may be manipulated through the action of the hand lever connection 20.

The power shaft 17 carries a bevel pinion 25 21 which meshes with a complementary bevel gear 22 on the sprocket shaft for transmitting power from one shaft to the other and revolve the power sprocket with the result previously described.

Previous to starting a cut, on a log for 30 instance, the implement may be frictionally engaged with the log to hold the rig to its work, and for this purpose a sharp toothed wheel 23 is employed at the underside of the yoke in Figure 1 and shown at 35 the top in Figure 3. This wheel is journaled by its shaft 24 in the lever arm 25, which is provided with a longitudinally extending slot 26, and pivoted through this slot at 27 on the housing or yoke. The 40 lever may be adjusted to dotted position in Figure 3 to project the wheel 23 so that it will pierce or penetrate the log, and may be turned for this purpose and held in fixed 45 position by means of the ratchet wheel 28 on the shaft 24, and the dog 29 that engages the ratchet wheel. The lever is held in adjusted position, when turned on its pivot 27, by means of the pawl 30 carried thereby, and is adapted to engage one of 50 the rack teeth of the segment 31 fixed to the yoke.

In felling trees, the yoke is held in hori-

zontal position and the straight flight, or working portion of the saw between the legs of the yoke, is held to its work for cutting a kerf, the thin bridge 5 of course following the working portion of the saw which is guided by the bridge. In felling trees of greater diameter than the length of the bridge, lateral notches are first cut at opposite sides of the tree to permit the passage therethrough of the legs of the yoke, and the saw cuts the kerf between these notches. The bridge 5 holds the cutting portion of the saw against flexure to insure proper action of the teeth, and of course guides the chain between the spaced members of the yoke. In cutting a horizontally disposed log, the rig is started with the saw on top of the log, after the toothed wheel 23 has been jammed into the periphery of the log for holding the rig. As soon as the cut is started, the wheel may be released, and the leg of the yoke will then hold the saw against side movement, as it, the leg, slides over the log, and the operator, by bearing down on the rig, makes the cut.

From the above description taken in connection with my drawings it will be evident that the device as illustrated may be manipulated with facility, and because of its simplicity in construction and operation is rendered capable of rapidity in action for performing its required functions.

Having thus fully described my invention, what I claim as new and desire to secure by Letters Patent is

The combination with a yoke shaped housing having spaced track plates therein, a guide bridge connecting the opposite ends of said yoke, and a guide wheel in one end of said yoke, a power wheel in the other end of the yoke and means for revolving said wheel, a chain saw comprising pivoted links adapted to ride on the edges of said track plates and fashioned with cutting teeth, sprocket teeth on some of said links adapted to pass between said plates, and anti-friction rollers on said power wheel co-acting with said sprocket teeth.

In testimony whereof I affix my signature.

EDWARD P. ARSNEAU.
